UNITED STATES PATENT OFFICE.

ALBERT WANNER, JR., OF HOBOKEN, NEW JERSEY.

ROCKING-CHAIR.

No. 893,289.

Specification of Letters Patent.

Patented July 14, 1908.

Application filed March 25, 1907. Serial No. 364,237.

To all whom it may concern:

Be it known that I, ALBERT WANNER, Jr., a citizen of the United States, residing in the city of Hoboken, county of Hudson, and 5 State of New Jersey, have invented certain new and useful Improvements in Rocking-Chairs; and I do hereby declare the following to be a full, clear, and exact description of the invention, such as will enable others 10 skilled in the art to which it appertains to make and use the same, reference being had to the accompanying drawings, and to letters of reference marked thereon, which form a part of this specification.

15 In the manufacture of the simpler types of chairs, such as bent-wood chairs, the-back-and-back-leg structure, the seat, the front legs and the leg brace are usually made and shipped separately to be afterwards assembled 20 at the place of ultimate distribution to the trade. It of course complicates this operation and makes it more expensive and otherwise hazardous in point of economy to be compelled to take into consideration 25 special types of chairs, such as rocking chairs, since the demand for them is of more or less unstable character and a quantity of rocking chairs made up according to one style is frequently without a market a short time thereafter, 30 owing to a change in style.

My invention has for its object, among other things, to provide a simple rocker structure which may be packed in compact form and be readily assembled with the back-and-back-leg structure of any ordinary chair 35 of the "straight" kind without the use of other means than screws or the like to hold the parts together and which will impart to the whole chair structure great strength 40 and durability. My invention makes it possible to avoid the loss attending making up complete rocking chairs suited in style to "straight" chairs and substantially every part of each of which is adapted only for every 45 other part; the manufacturer may make up any desired quantity of the component parts of plain or "straight" chairs and of the rocker structures and as rocking chairs are called for the back-and-back-leg structures may be 50 combined with the rocker structures to form rocking chairs of a style suitable to "straight" chairs to be used in a suite or set therewith.

55 My invention will be found fully illustrated in the accompanying drawing, wherein, Figure 1, shows my invention in perspective; Fig. 2 is a side view of a rocking chair

constructed in accordance with my invention, the dotted outline showing that the back-and-back-leg structure is adapted for a chair of the "straight" type primarily; Fig. 60 3 is a perspective view of the rocker-structure; and Figs. 4 and 5 are detail views illustrating a certain brace.

In the drawings *a* is the usual back-and-back-leg structure of an ordinary "straight" 65 chair, *b* is its seat, and *d* its front legs shown in dotted outline in Fig. 2. *e* designates the rockers and *f* a rung or brace connecting them in their rear portions; these parts may be of conventional form, as shown with a view to 70 reducing the cost of manufacture and extending the applicability of the rocker structure as far as possible to various styles or designs of chairs of the simpler type.

g is an arched frame carried by each rocker 75 and suitably affixed thereto in some permanent and substantial manner. The front portion *h* except for a slight reverse curve as shown in Fig. 2, which imparts strength as well as a graceful effect to the chair, is approximately straight; at its upper end said front portion merges into the curved rear portion *i*, the point of merger being a rather sharp bend *j*. This formation is doubly strong because of the arch shape and because 85 the portion of the frame that is to act principally in supporting the load to be borne by the frame, to wit its front portion, extends substantially perpendicularly from the rocker to the highest point of the frame before merging 90 into the rear portion *i*.

Having assembled the parts *e*, *f* and *g* as shown in Fig. 3, the same are ready for combining with the back-and-back leg structure and seat of a chair of the "straight" type, 95 and this is accomplished as follows: The legs of the back-and-back-leg structure having been first cut off so as to adapt it, in point in height, to use in a rocking chair, said structure is arranged on the rocker structure as 100 shown in Fig. 2, whereupon screws or bolts *k* or the like are employed to secure the seat to the frames *g* and the lower end portions of the rear parts *i* to the legs of the back-and-back-leg structure. No further securing 105 means will ordinarily be found necessary and the entire chair structure will then be extremely strong and durable.

The seat and back-and-back-leg structure may be reinforced where secured together by 110 a brace shown in Figs. 2, 4 and 5, said brace comprising the vertical part *l* which has a lon-

itudinal slot *m* for a bolt *n* and a hole *o* for a screw *p*, and horizontal part *q* and another vertical part *r*, said parts *l* and *r* being disposed at right angles to part *q* and adapted 5 to take the former against the inside face of the seat frame *s* and the latter against one of the legs of said structure, while part *g* bears against the under side of the frame *s*.

The holes *t* for the legs are first bored and 10 then the seat frame secured to the legs by passing the bolts through the legs and seat frame and slot *m* of the brace and then adjusting the bolt and nut to clamp the parts together, whereupon the screw *p* is passed 15 through the hole *o* and into the seat frame and one of the legs and another screw *v* driven through a hole *w* in the part *r* of the brace and into said leg.

The brace *m* comprises a strengthening 20 web *x* and the tangs *y* which will hold it in proper position until the bolt is properly secured.

I do not wish to be limited to any of the details herein set forth, what I claim being: 25 1. In a rocking chair, the combination of the back-and-back-leg structure, the seat carried by the back-and-back-leg structure, and a rocker structure comprising the rockers, means for bracing the same with respect

to each other and a one-piece arched frame 30 carried by each rocker, each frame having its front portion formed as a reverse curve and its rear portion as a relatively outward curve, said seat resting upon and being secured to the top portions of said frames and the lower 35 rear portions of said back-and-back-leg structure resting on the rockers and being secured at their extremities to the lower rear extremities of said frames, substantially as described.

2. In a chair, the combination of the back-and-back-leg structure, the seat secured thereto, a separate one-piece arched frame 40 secured to the under forward portion of the seat and supporting the same, each frame 45 having its front portion formed as a reverse curve and its rear portion as a relatively outward curve, the lower portions of the back-and-back-leg structure being secured at their 50 extremities to the lower rear extremities of said frames, substantially as described.

In testimony, that I claim the foregoing, I have hereunto set my hand this fifth, day of March, 1907.

ALBERT WANNER, JR.
